**WALL TELEPHONE SUBSCRIBER SET OR
SIMILAR ARTICLE**

Herbert Krämer, Furstenfeldbruck, and Herbert Hoher,
Germering, Germany, assignors to Siemens Aktien-
gesellschaft, Berlin and Munich, Germany

Filed Sept. 26, 1973, Ser. No. 400,804

Claims priority, application Germany Mar. 28, 1973

Term of patent 14 years

Int. Cl. D14—03

U.S. Cl. D26—14 A

Fig.1

Fig.2

FIG. 1 is a side elevation of a wall telephone subscriber set showing our new design; and

FIG. 2 is a front elevation thereof.

The side opposite FIG. 1 is substantially the same as the side shown with the exception of the telephone extension cord.

We claim:

The ornamental design for a wall telephone subscriber set or similar article, as shown and described.
